CHESTER W. LYMAN, OF NEW YORK, N. Y.

HOLDER AND SEVERING DEVICE FOR PAPER-ROLLS.

1,246,446.

Specification of Letters Patent. Patented Nov. 13, 1917.

Application filed December 18, 1913, Serial No. 807,402. Renewed April 12, 1917. Serial No. 161,679.

To all whom it may concern:

Be it known that I, CHESTER W. LYMAN, a citizen of the United States, residing at the city, county, and State of New York, have invented certain new and useful Improvements in Holder and Severing Devices for Paper-Rolls; and I do hereby declare the following to be a full, clear, and exact description of the invention, such as will enable others skilled in the art to which it appertains to make and use the same.

My invention relates to fixtures for holding rolls of paper, and for severing therefrom strips which have been drawn off to the appropriate length. It has been particularly developed for use in connection with the rolls of paper toweling which have in recent years come into wide use. The object of the invention is to provide a simple and effective device of this character from which the paper may be drawn and severed by the user, with one hand, so as to avoid the inconvenience attendant upon the use of both hands, particularly when the hands are wet.

The invention consists broadly in providing a rotatable paper-roll support of such character that the paper may be drawn from the roll freely at a convenient angle until the desired quantity has been unrolled, but upon slightly changing the angle of withdrawal of the paper, the roll will be positively locked against rotation, thereby permitting the paper to be torn off. This object may be effected, for example, by causing the change in the angle of withdrawal of the paper to throw or drop a locking pawl into engagement with a ratchet wheel on the rotatable roll support. For the purpose of aiding in the severing of the paper after the roll is locked, I may conveniently provide a serrated or straight edge constituting a cutter against which the paper is drawn when its angle of withdrawal is changed; and in the preferred embodiment of the invention hereinafter illustrated and described the cutter is employed as the instrument through which the locking pawl is actuated. In this preferred arrangement, the cutter, upon being engaged by the paper, acts to stop the rotation of the roll, thereby permitting the tearing off of the paper along the straight

edge, and preventing overrunning. The arrangement is preferably such that the straight edge will return to the position in which it frees the roll by gravity, and the free end of the paper will hang below the straight edge in a convenient position to be grasped for tearing off another strip.

In connection with my invention, I provide a suitable arrangement by which the paper tube which constitutes the core of the roll is held against rotation on the shaft of the roll support, as will be understood from the following description, and I have furthermore described and claimed certain particular features of novelty which, in the specific form disclosed, are not essential to the invention, but which I prefer to employ.

In the drawings, Figure 1 is an end elevation of the fixture with the roll of paper in position and showing in dotted lines the position of the cutter and paper when the strip is being torn off;

Fig. 2 is a front elevation of the same parts, showing the paper and the cutter in the position which they have assumed by gravity, and in this figure a portion of the roll is broken away to show more clearly the controlling pawl and ratchet and a convenient means for holding the roll against rotation on the shaft;

Fig. 3 is a fragmentary section of the end of the shaft showing in greater detail the mechanism for holding the roll against rotation thereon; and

Fig. 4 is a cross-section on the line 4—4 of Fig. 3.

Similar letters of reference indicate like parts in the several figures.

A represents a support, such as a wall, or the like, to which the base-plate B of the fixture is attached, and the base-plate has two outwardly extending bracket arms B' which are provided with bearings C, C' for the roll supporting shaft D. It will be understood that one of the bearings, as C', will be open at the top so that the end of the shaft may be dropped into it after the other end has been inserted in the bearing C. The roll of paper shown is of the kind now so generally used for towels and is wound on a paper or pasteboard tube E of a length equal to the width of the paper and

- slightly less than the length of the shaft D, upon which the tube is slipped and which constitutes the axle for the paper roll. As shown, the shaft D is of metal tubing and 5 is provided at one end with projecting shoulders or wedges G adapted to enter corresponding slits or notches in the tube E, as shown in Figs. 2, 3 and 4, for the purpose of holding the paper roll against rotation 10 on the shaft, and thereby causing the shaft to rotate when the paper is drawn from the roll. In the ends of the shaft D are tightly fitted plugs H' carrying the hubs or trunnions upon which the roll is mounted in the 15 bearings C, C'. The plug in that end of the roll which abuts the bearing C' has a simple cylindrical extension constituting the hub which lies in that bearing, but the plug in that end of the roll which abuts the bearing C is of the modified form shown in Fig. 20 3 of which the portion H' of greater diameter carries a ratchet wheel J while the reduced portion I is of a size to fit within the bearing C.
- 25 The cutter consists of the depending arms K, K' pivoted to the bracket arms B', as shown, and carrying at their lower end the serrated edge L'. Although the edge L' is shown serrated, it will be understood that a 30 straight edge may be employed if preferred. The arm K carries a pawl or dog L adapted to engage the teeth of the ratchet wheel J when the arms are moved outwardly through a small angle, and a stop M is preferably 35 provided against which the depending cutter arm K rests when hanging in the position shown in full lines in Fig. 1.
- The operation of the device is as follows: 40 The shaft D is inserted in the tube E until the wedges G engage the slits or notches in the tube E, and thereby hold the paper roll against rotation on the shaft. The hub I is then inserted in the bearing C and the projecting hub at the other end of the roll 45 is laid in the bearing C'. When it is desired to tear off a strip of paper, the user with one hand grasps the paper and draws it downwardly until the desired length has been unrolled and then draws it outwardly 50 against the cutter until the part K engages the teeth of the ratchet wheel J, thereby locking the roll against the further rotation. whereupon the paper is severed by tearing it along the serrated edge as will be readily 55 understood. When this has been accomplished, the cutter returns by gravity to the position shown in Fig. 1 in full lines, in which the paper roll is again freed, and because of the angular relation of the paper 60 to the cutter, the free end of the paper will hang below the cutting edge, as illustrated in Fig. 2, and may conveniently be grasped for tearing off another strip.

It will be observed that in the fixture de-

scribed simple means are provided for locking the paper roll on the shaft of the holding fixture, and that the paper may be drawn out the desired length and then severed from the roll by a simple and natural movement which may be accomplished by one hand, 70 and that the cutting action positively locks the roll to assist the severing and to prevent overrunning. In addition to the convenience of operation, the fixture has the advantage that unperforated rolls of paper may be employed, thus cheapening the manufacture and at the same time enabling each user to decide for himself the length of paper 75 which he will use.

Although I have thus described in detail 80 the preferred embodiment of my invention, I do not wish it to be understood that the particular form thus specifically described cannot be departed from. On the contrary, it is, so far as I know, broadly new to provide a rotatable support from which the paper may be freely withdrawn at a convenient angle and which by slightly changing the angle of withdrawal of the paper is positively locked to permit the tearing off 90 of the desired length of the paper strip; and the claims appended hereto should have a correspondingly broad interpretation.

What I claim is:

1. A holder and severing device for paper 95 rolls comprising a rotatable roll-support from which the paper may be freely drawn at a convenient angle, a locking element carried by said roll-support, and a second locking element actuated by the paper upon 100 slightly changing the angle of withdrawal thereof to engage the first locking element and positively lock the roll-support against rotation.

2. A holder and severing device for paper 105 rolls, comprising a rotatable roll support carrying a ratchet wheel, a locking pawl normally withheld from engagement with the ratchet wheel, and means actuated by the paper at a given angle of withdrawal to 110 bring the pawl into engagement with the ratchet wheel and positively lock the roll support against rotation.

3. A holder and severing device for paper 115 rolls, comprising a rotatable roll support from which the paper may be withdrawn at a convenient angle, said support being provided with means for holding a paper roll against rotation with respect thereto, and a locking device actuated by the paper upon 120 slightly changing the angle of withdrawal thereof to positively lock the roll support against rotation.

4. A holder and severing device for paper 125 rolls comprising a rotatable support for the roll, a locking element carried by said support, a cutter, and a second locking element actuated by the contact of the paper with

the cutter to engage the first locking element and prevent the turning of the rotatable support during the severing operation.

5. A holder and severing device for paper rolls, comprising bracket arms, a shaft rotatably supported therein, a ratchet on the shaft, and a pivoted cutter carrying a pawl adapted to engage the ratchet and prevent

the rotation of the roll during the severing operation. ¹⁰

In testimony whereof I affix my signature in presence of two witnesses.

CHESTER W. LYMAN.
